[57] CLAIM

The ornamental design for a scraper arrangement pertaining to food processors, as shown and described.

DESCRIPTION

FIG. 1 is a front perspective upper view of a scraper arrangement pertaining to food processors in accordance with my design.

FIG. 2 is a front perspective lower view thereof.

FIG. 3 is a right side elevational view thereof.

FIG. 4 is a front elevational view thereof; and,

FIG. 5 is a rear elevational view thereof.

The upper, outer portions of the symmetrical scraper outer ring, spokes, and symmetrical scraper inner ring not visible in FIG. 1 have the same appearance as corresponding portions of those elements of the design that are visible in FIG. 1. The lower inner portions of the symmetrical scraper outer ring, spokes, and symmetrical scraper inner ring not visible in FIG. 2 have the same appearance as corresponding portions of those elements of the design that are visible in FIG. 2.
